UNITED STATES PATENT OFFICE.

HENRY G. RUNNE, OF ROCHESTER, NEW YORK, ASSIGNOR OF ONE-HALF TO CHARLES L. TOWNSEND, OF ROCHESTER, NEW YORK.

DESIGN FOR A TOY.

53,343:

Specification for Design.

Patented May 20, 1919.

Application filed March 18, 1919. Serial No. 283,436. Term of patent 14 years.

To all whom it may concern:

Be it known that I, HENRY G. RUNNE, a citizen of the United States, residing at Rochester, in the county of Monroe and State of New York, have invented a new, original, and ornamental Design for Toys, of which the following is a specification and of which the accompanying drawing is a representation.

The figure is a perspective view of my new design.

I claim:

The ornamental design for a toy, as shown.

HENRY G. RUNNE.
